TURBOGENERATOR FOUNDATION

Donald J. Griffith, Denver, Colo., assignor of one-half to Joseph P. Ruth, Denver, Colo.

Application December 15, 1952, Serial No. 326,027

2 Claims. (Cl. 248—13)

This invention relates to beds or foundations for the support of mechanical assemblies, and more particularly to foundations for the support of large turbogenerators, and has as an object to provide a novel and improved foundation characterized by facility of design and construction, economy, and practical operative advantage.

A further object of the invention is to provide a novel and improved turbogenerator foundation accommodative of the auxiliary equipment required by such units.

A further object of the invention is to provide a novel and improved turbogenerator foundation accommodative of the loads and stresses imposed thereon.

A further object of the invention is to provide a novel and improved turbogenerator foundation conservative of space and material.

A further object of the invention is to provide a novel and improved turbogenerator foundation susceptible of convenient adaptation to meet the support requirements of diverse mechanical units throughout an extensive range of unit types and sizes.

A further object of the invention is to provide an improved turbogenerator foundation adapted for development at the site of its installation through the use of normally-available materials and the application of common skills.

A further object of the invention is to provide a novel and improved turbogenerator foundation reactive to the dynamic loads and variable load factors imposed thereon during operation of the mechanical unit supported thereby, thus to counteract, absorb, and minimize adverse effects of such load and load factors upon both the mechanical unit and its support.

With the foregoing and other objects in view, my invention consists in the construction, arrangement, and unitary combination of elements as hereinafter set forth, pointed out in my claims, and illustrated by the accompanying drawings, in which—

Figure 1 is a perspective view of a turbogenerator foundation typically embodying the concept of the invention as developed for practical use, broken lines in the view representing a conventional turbogenerator unit supported on the foundation in a conventional position of use.

Figure 2 is an end elevation of the foundation shown in Figure 1 prior to mounting of the turbogenerator unit thereon.

Figure 3 is a top plan view of the foundation shown in Figure 2.

Figure 4 is a side elevation of the foundation represented by Figures 2 and 3.

The improved foundation of the present invention is preferably a monolithic masonry unit cast or formed in the place of its use from reinforced concrete, the techniques pertinent to such construction, including the design and arrangement of the reinforcement, being fully and widely understood. In common with similar conventional foundations, the improvement includes a heavy, solid, generally-rectangular base block 10 of an area at

2

least as great as, and preferably exceeding, that of the deck which is to carry the mechanical unit and of a thickness, strength, and mass appropriate to withstand the loads imposed thereon. In accordance with established practice, 5 the base block or slab 10 will be dimensioned to provide a bearing area in contact with the material underlying the foundation adequate to support the ultimate load with a weight distribution appropriate to the bearing capacity of such material.

10 Since conventional construction and installation of turbogenerators requires readily-accessible space beneath the unit for the accommodation of auxiliary equipment, the improved foundation includes a rigid, generally-rectangular deck 11 having an area adequate to support the turbogenerator unit 12 for which the foundation is designed. The deck 11 is apertured, as at 13, for the accommodation of extensions and connections characterizing the conventional turbogenerator unit. Bearing plates 14 and appropriate deck marginal extensions 15 are utilized in any desired arrangement for such coaction with elements of a particular unit 12 as may be expedient to mount the unit in a suitable supported relation with the upper deck surface.

As should be obvious, the base block 10 is horizontally 25 disposed and the deck 11 is supported on and in spaced relation above the block 10 with the upper surface horizontal, that which distinguishes the present invention being the location, form, and arrangement of the means supporting the deck on the base block to provide a materially 30 improved foundation. Significantly deviating from the usual practice of supporting the deck 11 from the base 10 by means of posts or columns disposed under the four corners of the deck, and in certain instances under other portions of the deck in addition to such corner support, the 35 deck of the improved foundation is supported solely by a pair of like pillars 16 similarly disposed in spaced, parallel relation and perpendicular to the deck top plane beneath and intermediate the length of the deck, each pillar having a width, or a dimension longitudinally of the deck, on the 40 order of one-third to one-half of the deck length where the pillars engage the base block 10 and being expanded upwardly and outwardly at each side to engage and merge into the deck side margins through triangular shoulders or buttresses 17 effective to greatly extend the zone of 45 pillar and deck margin interengagement. The pillars 16 are of such thickness and are so reinforced as to adequately support the deck and turbogenerator loads, both static and dynamic, in accord with usual engineering practice, and the pillars 16 and deck 11 are so dimensioned 50 and interrelated as to provide a clear space between the pillars 16 communicating with the apertures 13 and preferably to provide a lateral shoulder extension of the base block 10 at the outer side of and projecting beyond each pillar 16, as at 18.

55 While the several views of the drawing represent the pillars 16 as centered beneath the transverse median line of the deck 11, it is to be understood that the deck is so dimensioned as to receive and support a particular turbogenerator unit 12 and is so related with the supporting 60 pillars 16 as to balance the deck and its load relative to the pillar center lines or planes transversely of the base block 10; the said pillar center lines or planes being coincident with the transverse center line of the base block. The improved foundation being symmetrical with respect 65 to its longitudinal vertical median plane and being arranged to balance the imposed load about a transverse axis coincident with the pillar transverse center lines or planes, it is manifest that the foundation is conditioned, through incidence of all imposed loads upon the base block 10 70 through the two pillars 16, to adequately sustain all static loads of the assembly and to advantageously damp, moderate, counteract, and absorb the dynamic loads to modify

their destructive effect upon the unit 12 or any elements of the foundation; the cantilever mounting of the deck ends permitting the structure to yield within the elastic limit thereof as a result of changes in load conditions due to the dynamic nature of the load. Use of but the two pillars 16 in the disposition and arrangement shown and described very much facilities installation and maintenance of the auxiliary equipment pertinent to the operation of the unit 12, and support of the deck 11 by the pillars in the manner represented contributes to economy of foundation production, as well as efficient unit installation and operation.

Since changes, variations, and modifications in the form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. A foundation supporting a load having rotating parts disposed on a horizontal axis of rotation, said foundation comprising a base, a generally rectangular horizontal load supporting deck spaced above said base, a pair of vertical pillars extending between said base and said deck and constituting the sole means for supporting said deck, said pillars being of a width of the order of one-third to one-

half of the length of said deck and being aligned with adjacent opposite sides thereof and intermediate the length of said deck in such a location that a vertical plane through the center of gravity of said deck and said load coincides with the vertical center line of said pillars whereby the opposite ends of said deck and load carried thereby overhang said pillars with said deck and load balanced about a horizontal axis disposed in said vertical plane and means on said deck spaced inwardly of the inner side surfaces of said pillars for securing said load to said deck.

2. A foundation as defined in claim 1 in which said base is generally rectangular and in which the center of gravity of said load and said deck is disposed substantially in vertical alignment with the geometric center of said base.
